UNITED STATES PATENT OFFICE.

DAVID A. DIXON AND BENJAMIN F. WILLIAMSON, OF ST. LOUIS, MISSOURI,
ASSIGNORS TO HAYDENS & ALLEN, OF SAME PLACE.

SIDE-SADDLE TREE.

SPECIFICATION forming part of Letters Patent No. 243,227, dated June 21, 1881.

Application filed May 2, 1881. (Model.)

To all whom it may concern:

Be it known that we, DAVID A. DIXON and BENJAMIN F. WILLIAMSON, citizens of the United States, residing at St. Louis, in the county of St. Louis and State of Missouri, have invented new and useful Improvements in Side-Saddle Trees, of which the following is a specification.

The object of this invention is to form a strong light side-saddle tree which shall be comfortable both for the rider and for the horse.

To such end it consists, first, in the saddle-tree provided with solid concaved sides, and having longitudinal metal braces or straps applied in the concave, and vertical braces or straps connected with the longitudinal braces and secured to the saddle-tree; second, in the saddle-tree for side-saddles provided with solid concaved sides and rear portion, leaving the seat projecting laterally beyond the concaved sides, and having the longitudinal and vertical strengthening-braces; third, in the tree for ladies' side-saddles, having deeply concaved sides, a laterally-projecting seat, and an elevated pommel concaved on its under side, all as hereinafter fully described.

In the accompanying drawings, Figure 1 is a top or plan view of the saddle-tree constructed in accordance with our invention. Fig. 2 is a view of one side of the tree, and Fig. 3 is a view of the opposite side thereof. Fig. 4 is a section taken on the line $x-x$, Fig. 1.

A A indicate the solid seat-bars of the tree, which are properly curved to form the seat.

B indicates the horizontal bar at the forward ends of the seat-bars, said horizontal bar forming the pommel of the saddle.

The horn C rises from the juncture of the pommel and one of the seat-bars, and instead of having its inner side parallel with a line, $y-y$, taken centrally through the greatest length of the saddle, the said inner side is rounded and arranged at an angle diverging from the said line to the front of the tree. To effect

this arrangement of said inner side the horn is twisted, as illustrated in the plan view, Fig. 1. By such arrangement the leg of the rider will not be chafed or injured, as is frequently the case in the side-saddles heretofore made.

The solid sides of the tree are deeply concaved, as at D D, so as to render the same lighter and stronger than the trees heretofore made with a sharp angle at the juncture

of the seat-bars and the depending sides of the tree.

It will be seen that the seat flares out or projects laterally to some extent beyond the sides of the tree, whereby a broad seat is obtained which will be comfortable for the rider.

The tree is braced and strengthened by the metal braces, straps, or plates E F, the former being secured to the under side of the seat-bars and arranged in approximately horizontal planes, and also secured to the intersecting metal braces, straps, or plates F, which are secured to the sides of the tree, as illustrated in the views showing side elevations of the tree.

The edge of the seat will be made rounding or with a roll, G, whereby the covering will not be injured, the seat will be agreeable to the rider, and the weight of the rider be evenly distributed thereon.

The pommel B, instead of being made straight on its under side, is curved, as at H, whereby the pommel will be elevated above the back of the horse. This not only prevents the chafing of the horse's back, but also admits of the circulation of air between the same and the pommel.

What we claim is—

1. The saddle-tree provided with solid concaved sides, and having the longitudinal metal braces or straps E applied in the concave, and the vertical braces F connected therewith and secured to the saddle, substantially as shown and described.

2. The saddle-tree for side-saddles, provided with solid concaved sides and a rear portion, leaving the seat projecting laterally beyond the sides, and having the longitudinal and vertical strengthening-braces, substantially as described.

3. The tree for ladies' side-saddles, having the deeply-concaved sides, the laterally-projecting seat, and the elevated pommel concaved on its under side, substantially as described.

In testimony whereof we have hereunto set our hands in the presence of two subscribing witnesses.

DAVID A. DIXON.
BENJAMIN F. WILLIAMSON.
